UNITED STATES PATENT OFFICE.

HERBERT J. STRAKER, OF NORTH ATTLEBORO, MASSACHUSETTS.

DESIGN FOR A PURSE-TOP OR SIMILAR ARTICLE.

SPECIFICATION forming part of Design No. 36,105, dated October 14, 1902.

Application filed August 19, 1902. Serial No. 120,265. Term of patent 3½ years.

To all whom it may concern:

Be it known that I, HERBERT J. STRAKER, a citizen of the United States, residing at North Attleboro, in the county of Bristol and State of Massachusetts, have invented a certain new, original, and ornamental Design for a Purse-Top or Similar Article, of which the following is a specification.

The figure is a face view of my design embodied in a purse-top, wherein similar letters of reference indicate like parts.

As shown in the drawing, the leading or material feature of my design is a centrally-located escutcheon a, surmounted by an orchid-bud b and intertwined foliates. Contiguous to one side of the escutcheon is the representation of a full-blown orchid d. Intermediate this orchid and the purse-top extremity is a partially-blown rose e, with a depending bud and tendrils, while it is surmounted by the representation of another bud f and a cluster of rose foliates g, the floral decoration springing from the end of the purse-top toward the escutcheon. The other purse-top extremity is ornamented by 25 the representation of an orchid h, surmounted by a bud i and foliates j, the whole springing from the end of the purse-top toward the escutcheon, while intermediate the latter and the escutcheon is the representation of a full-blown jonquil c. Scattered at intervals intermediate the elements described are representations of forget-me-nots.

It is evident that my design is applicable to bag-tops and similar articles. 35

Having thus described my invention, what I claim is—

The ornamental design for a purse-top or similar article, as herein shown and described.

In testimony whereof I have affixed my signature in presence of two witnesses. 40
